ABSTRACT OF THE DISCLOSURE

This disclosure relates to a capping machine for applying screw caps to containers. A principal feature of the capping machine is the adaptability thereof to a conventional conveyor system wherein the guide portion of the conveyor system is utilized to hold the container against rotation while the capping machine applies a cap thereto. The capping machine is mounted independently of the conveyor and is adjustable so as to align the same with the conveyor and properly vertically position the same in alignment with the container neck. The capping machine includes a capping mechanism having a plurality of cap rotating members which are individually adjustable for the purpose of both accommodating caps of different diameters and varying the pressure engagement of the cap rotating members with caps.

This invention relates in general to new and useful improvements in capping machines, and more particularly to a capping machine for applying screw caps to containers.

A primary feature of this invention is to provide a capping machine which may be readily mounted with respect to an existing conveyor for conveying filled containers wherein the conveyor includes a guide which is cooperable with a filled container to prevent rotation thereof, the capping machine being readily mountable adjacent the existing conveyor and having a capping mechanism overlying the path of movement of containers for applying screw caps to the containers while they are being conveyed by the conveyor and held against rotation by the associated guide means.

A principal feature of the capping machine is the mounting thereof which includes an upright having a vertically adjustable coupling at the upper end thereof with the capping mechanism being carried by one half of the coupling, and there being means provided for connecting the upper portion of the upright to an existing conveyor so as to transversely position the capping mechanism in overlying relation to the conveyor.

Still another feature of this invention is the provision of a novel capping mechanism which is adapted to overlie a path of movement of containers and to apply screw caps to the containers, which containers are fixed against rotation while moving along the predetermined path. The capping mechanism includes a plurality of cap rotating units, each of which includes a pair of opposed cap rotating members disposed in spaced relation on opposite sides of the path of movement of a container cap for engaging the same and rotating the cap to screw it onto a container. The individual cap rotating members are transversely adjustable so as to accommodate various size caps and at the same time so as to adjust the pressure engagement of the cap rotating members with caps.

A further feature of this invention is the provision of a simple drive for the cap rotating members whereby the cap rotating members at each side of a path of cap travel may all be simultaneously driven from a single drive unit and still permit individual transverse adjustment of the cap rotating members, all of the cap rotating members being driven by an endless drive member having associ-

2

ated therewith a slack take up mechanism so as to compensate for variations in positions of cap rotating members.

With the above and other objects in view that will hereinafter appear, the nature of the invention will be more clearly understood by reference to the following detailed description, the appended claims and the several views illustrated in the accompanying drawings:

In the drawings:

10 FIG. 1 is a schematic plan view of a container filling and capping mechanism employing the capping machine of this invention.

15 FIG. 2 is an enlarged plan view of the capping machine with the top wall of the housing of the capping mechanism being partially broken away to show the specific internal details of the capping mechanism.

20 FIG. 3 is a fragmentary longitudinal vertical sectional view taken along the line 3—3 of FIG. 2 and shows specifically the relationship of the capping mechanism to containers being capped.

25 FIG. 4 is a fragmentary transverse vertical sectional view taken along the line 4—4 of FIG. 3 and shows further the specific details of the capping mechanism as well as the specific details of the support for the capping mechanism.

30 Referring now to the drawings in detail, it will be seen that there is illustrated in FIG. 1 the over-all arrangement of a container filling and capping mechanism, which mechanism is generally identified by the numeral 10. The mechanism 10 includes a combined guiding and conveying assembly which is generally identified by the numeral 11 for moving containers along a predetermined path. The combined guiding and conveying assembly 11 is particularly adapted to handle containers which are 35 rectangular or square in cross section, such as the containers 12.

35 The containers 12 are delivered by the mechanism 11 into a conventional type of filler, which is identified by the numeral 13, wherein the containers 12 are automatically filled. After the containers 12 are filled, it is 40 desired that the containers be immediately capped. Accordingly, they first pass beneath the feed chute 14 of the conventional cap orienting and feeding mechanism which is generally identified by the numeral 15. As a cap, which is identified by the numeral 16, is seated on a container 45 12, the container 12 passes beneath the capping machine, which capping machine is the subject of this invention and is generally identified by the numeral 17. The capping machine 17 automatically presses the cap 16 down on the container and rotates the cap to screw the cap to a container 50 closing position.

55 Referring now to FIG. 4 in particular, it will be seen that the combined guiding and conveying mechanism 11 includes a lower conveyor mechanism 18 and an upper guide unit 20. The conveyor mechanism 18 may be of any construction although at a minimum, it requires an endless conveyor belt 21 which passes around a pair of supporting rollers 22 at the opposite ends of its travel. In addition, in the vicinity of the capping machine 17, the upper run of the conveyor belt 21 must be supported by a suitable support member which is identified by the numeral 23. The illustrated support member is of an inverted channel configuration and desirably may extend the full length of the conveyor assembly 18.

60 The guide unit 20 is preferably of an extremely simple form and may consist of rods 24 which are preferably arranged in pairs on opposite sides of the intended path of movement of the containers 12. The pairs of rods 24 are transversely spaced a distance substantially equal to the width of the container 12 and since the container 12 is rectangular in cross section, as is clearly shown in FIG. 1, the guide rods 24 restrict the rotation of the container

12 to a very small angle during the application of a cap **16** thereto.

At this time it is pointed out that the illustrated container **12** is in the form of a milk bottle or other liquid container and has a reduced diameter neck portion **25** to which the cap **16** is applied. However, the exact configuration of the container **12** is immaterial as far as this invention is concerned except that it must be generally rectangular in outline so that the guide unit **20** prevents the same from rotating when the cap is being applied thereto and at the same time the conveyor assembly **18** can freely move the container along the predetermined path during the application of the cap **16** thereto. Exceptions to the foregoing are round containers having enough weight to withstand the torque required to tighten the cap. For example, one gallon round glass containers.

At this time it is pointed out that normally the filler **13** and the combined guiding and conveying assembly **11** are already a part of a filling line. In accordance with this invention, it is proposed to utilize the combined guiding and conveying assembly **11** both for the purpose of supporting a container during the capping thereof and for holding the container being capped against rotation during the application of the cap thereto.

Reference is now made to FIGS. 2, 3 and 4 wherein the specific details of the capping machine **17** are shown. The capping machine **17** basically includes a support, which is identified by the numeral **30**, and a capping mechanism which is identified by the numeral **31**. The support **30** is intended to be fixedly mounted adjacent the existing combined guiding and conveying mechanism **11** and includes an upright **32** which has the lower end thereof mounted in any desired manner such as by means of a base **29**.

At the upper end of the upright **32** there is a vertically adjustable coupling, which is identified by the numeral **33**, which coupling supports the capping mechanism **31** from the upright **32**.

The coupling **33** includes a lower support plate **34** and an upper support plate **35** which are rigidly secured to the upper portion of the upright **32** and extend horizontally therefrom. The support plates **34** and **35** are coupled together by a vertical support plate **36** which extends above the upper support plate **35**.

A vertically adjustable support plate **37** is mounted in face-to-face engagement with the fixed support plate **36** and is clamped thereagainst in a vertically adjusted position by a pair of clamp bolts **38** which are releasably carried by the support plate **36** and which extend through vertical slots **40** (FIG. 3) in the support plate **37**. The upper end of the support plate **37** is provided with a flange **41** to which a housing **42** of the capping mechanism **31** is secured.

The adjustable support plate **37** is provided with a nut element **42** which projects towards the upright **32** through a vertical slot **43** in the support plate **36**. The nut element **42** has threadedly engaged therein and passing therethrough an adjusting screw **44** which is suitably carried by the plates **34** and **35** and which extends materially thereabove and terminates in a gripping element **45** to facilitate the rotation thereof. When it is desired to vertically adjust the capping mechanism **31**, the bolts **38** are slightly loosened and the support **37** vertically adjusted by turning the screw **44**.

At this time it is pointed out that the capping mechanism **31** is retained in transverse alignment with the combined guiding and conveying mechanism **18** by means of adjustable connecting strap assemblies **46** which extend between the coupling **33** and the conveyor assembly **18**. The strap assemblies **46** include first and second slotted straps **47** and **48** which are adjustably connected together by a bolt **50**. The strap **48**, in turn, is vertically adjustably secured to the frame member **23** by means of a bolt **51**.

It is to be noted that the housing **42** of the capping mechanism **31** is generally rectangular in outline and includes a bottom wall **52**, a pair of longitudinal walls **53** and

and **54**, a pair of end walls **55** and **56** and a removable cover **57**.

The bottom wall **52** is provided with a central longitudinal opening **58** therethrough through which a cap depressing belt **60** depends. The belt **60**, as is best shown in FIG. 2, is supported by a drive roll **61** and an idler roll **62** which are suitably supported on the bottom wall **52**. The drive roll **61** is driven by a suitable electric motor **63** through a coupling **64** so that the rate of movement of the belt **60** is substantially the same as that of the conveyor belt **21** to support the upper end of a container **12**.

The capping mechanism **31** also includes a plurality of cap rotating units which are spaced longitudinally of the housing **42**. Each cap rotating unit includes two cap rotating members **66** and **67** which are disposed in opposed relation on opposite sides of the path of travel of the caps **16** and lying in the general plane of the cap, as is best shown in FIG. 4. Each of the cap rotating members **66** and **67** is carried by a spindle **68** which is rotatably mounted within a housing **69** and has secured to the upper end thereof a drive sprocket **70**. Each housing **69** includes a slide block **71** fixedly attached thereto and mounted within a housing **72** carried by the bottom wall **52** for transverse sliding movement. Each slide block **71** has coupled thereto an adjusting screw **73** which is rotatably carried by the respective side wall of the housing **42** and which is provided with an exposed knob **74** to facilitate the rotation thereof to adjust the relative position of the associated cap rotating members **66** or **67**.

It will be readily apparent from the foregoing that the individual cap rotating members **66** and **67** may be adjusted so as to accommodate between opposed cap rotating members **66** and **67** various sizes of caps **16**. In addition, the cap rotating members **66** and **67** may be transversely adjusted so as to vary the pressure engagement thereof with a cap.

Referring to FIGS. 2 and 4 in particular, it will be seen that all of the sprockets **70** of the cap rotating members **66** are simultaneously rotated at the same speed through a drive chain **75** which is driven by a sprocket **76**. The sprocket **76** is, in turn, carried by and rotated by a motor **77** which is mounted on the side wall **53** of the housing **42**. It is to be noted that the cap rotating members **66** rotate in a counterclockwise direction so as to spin a cap engaged therewith in a clockwise direction.

It is also to be noted that all of the cap rotating members **67** are simultaneously driven by means of a chain **78** which is engaged with the driving sprockets **70** thereof. The chain **78** is driven by means of a drive sprocket **80** carried by and driven by an electric motor **82** which is mounted on the side wall **54** of the housing **42**. The chain **78** moves in a direction to rotate the cap rotating members **67** in a counterclockwise direction so as to effect the clockwise rotation of a cap engaged thereby.

At this time it is pointed out that in order to compensate for the transverse adjustment of the cap rotating members **66** and **67**, each of the chains **75** and **78** has associated therewith a slack take up sprocket **83** which is mounted on a swinging arm **84** and urged to a chain tensioning position by means of a spring **85**.

OPERATION

It will be readily apparent that after a container **12** has been filled by means of the filler **13**, it is moved longitudinally along the combined guiding and conveying assembly **11** to a position whereat it passes under the exit end of the sheet **14** from the cap feeding mechanism **15**. A properly oriented cap **16** is automatically picked up by the container **12** with the cap being spun slightly by the first set of cap rotating members **66** and **67** so as to be loosely, but squarely positioned on the container **12**.

As the container **12** moves to the right, as viewed in FIG. 3, it passes beneath the cap depressing belt **60** which also serves the function of cooperating with the conveyor **21** so as to stabilize the container **12** against

overturning in a longitudinal direction. With the container 12 so stabilized, the cap 16 is progressively turned and tightened by engagement with the others of the cap rotating members 66, 67. It is to be understood that the material of the cap rotating members 66, 67 may be varied so as to provide for varied gripping engagement with the cap. Also, the spacing between transversely adjacent cap rotating members 66 and 67 may be varied so as to produce different gripping effects on the caps 16 and thereby to provide for the exact degree of tightness of the caps 16.

It will be readily apparent that inasmuch as the container 12 is prevented from rotating by the guide rods 24 and is prevented from transversely overturning by these same guide rods and since the conveyor belt 21 and the cap depressing belt 61 cooperates to prevent overturning of the container in a longitudinal direction, the container 12 is automatically firmly supported during the application of the caps 16 thereto.

Although it is the primary intention of this invention to provide a capping machine which may be readily associated with an existing combined guiding and conveying assembly, it is also to be understood that the combined guiding and conveying assembly 11 may be furnished with the capping machine.

Although only a preferred embodiment of the capping machine has been specifically illustrated and described herein, it is to be understood that minor variations may be made therein without departing from the spirit of the invention.

I claim:

1. In combination with a conveyor assembly having a moving conveying member for supporting and transporting containers along a predetermined path, and fixed guide means on opposite sides of said container path for slidably engagement by containers and for preventing rotation of containers conveyed by said conveying member; a free standing capper removably mounted adjacent said conveyor assembly and having capping mechanism overlying said moving conveying member; said capping mechanism including cap rotating means for rotating screw-on caps on containers while the containers are being moved by said conveyor assembly and held against rotation thereby, an upstanding support separate and apart from said conveyor assembly and means mounting said cap rotating means on said support for selective vertical positioning relative to said moving conveyor member and said fixed guide means; and said cap rotating means including a plurality of cap rotating units for engaging and sequentially rotating a cap to screw such cap onto an associated container, each cap rotating unit including a pair of cap rotating members positioned in spaced opposed relation on opposite sides of the intended path of movement of caps, and means for rotating the cap rotating members of each pair in the same direction for cooperation to turn a cap passing therebeneath.

2. A capper particularly adapted for use in combination with an existing combined container guiding and convey-

ing mechanism of the type operable to move containers along a predetermined path while preventing rotation of the containers, said capper being of the type to apply screw-on caps and comprising a support adapted to be fixedly positioned relative to a container guiding and conveying mechanism and substantially independently, thereof, and a capping mechanism carried by said support for overlying a container guiding and conveying mechanism for tightening previously positioned caps on containers, said capping mechanism comprising a cap depresser for engaging a cap and urging the cap down onto a container in a level position at all times while the cap is being rotationally applied, and a plurality of cap rotating units for engaging and sequentially rotating a cap to screw such cap onto an associated container, each cap rotating unit including pair of cap rotating members positioned in spaced opposed relation on opposite sides of the intended path of movement of caps, and means for rotating the cap rotating members of each pair in the same direction for cooperation to turn a cap passing therebeneath, means for individually transversely positioning each of said cap rotating members to vary the spacing between cap rotating members of each cap rotating unit both to adjust for variations in cap size and to adjust the pressure engagement of said cap rotating members with a cap.

3. The capper of claim 2 wherein all cap rotating members disposed on each side of the path of cap movement are simultaneously driven from a single drive unit, said drive unit including a fixedly mounted power unit, an endless drive member and an automatic slack take-up mechanism for compensating for variations in the positions of said cap rotating members relative to each other and to the respective power unit.

4. The capper of claim 2 wherein said capper includes a housing having a bottom wall, and said means for individually transversely positioning each of said cap rotating members includes a slide block supporting each cap rotating member, said slide block being seated on said housing bottom wall for transverse sliding movement and a separate adjusting screw carried by said housing for each slide block connected to the respective slide block for both adjusting the relative position of the respective cap rotating member and maintaining the adjusted position thereof.
